Des. 202,453

Patented Sept. 28, 1965

202,453

CARRYING CASE FOR A BOOK AND RECORD

Lyle Kenyon Engel, East Chatham, N.Y., assignor of one-half to Pocket Books, Inc., New York, N.Y., a corporation of New York

Filed Oct. 28, 1964, Ser. No. 82,357

Term of patent 14 years

(Cl. D59—8)

FIG. 3

FIG. 1

FIG. 2

FIG. 4

FIG. 5

FIG. 1 is a top plan view of a carrying case for a book and record, embodying my new design;

FIG. 2 is a front elevational view thereof;

FIG. 3 is a rear elevational view thereof;

FIG. 4 is a side elevational view, the side opposite being identical thereto; and

FIG. 5 is a bottom plan view thereof.

I claim:

The ornamental design for a carrying case for a book and record, as shown and described.
